(57) **CLAIM**

The ornamental design for a dispensing device with ovoid body, as shown and described.

DESCRIPTION

FIG. 1 is a front view of a dispensing device with ovoid body showing our new design; and,

FIG. 2 is an exploded perspective view thereof.

The broken lines shown in the drawing disclosure are for illustrative purposes only and form no part of the claimed design.

The sides not shown in the drawing disclosure form no part of the claimed design.
